UNITED STATES PATENT OFFICE.

LOUIS CUVELIER, OF HALIFAX, NOVA SCOTIA, CANADA.

SHOE-HEEL.

1,368,902.

Specification of Letters Patent. Patented Feb. 15, 1921.

Application filed July 15, 1920. Serial No. 396,355.

To all whom it may concern:

Be it known that I, LOUIS CUVELIER, residing at Halifax, in the county of Halifax and Province of Nova Scotia and Dominion of Canada, have invented certain new and useful Improvements in Shoe-Heels; and I do declare the following to be a full, clear, and exact description of the invention, such as will enable others skilled in the art to which 10 it appertains to make and use the same.

This invention relates to improvements in shoe heels, and it has more particular reference to rubber heels for attachment to the usual leather heel.

15 The main object of the invention is to improve upon the construction of my prior Patent No. 1,108,975 granted to me on September 1, 1914.

In the above named patent is shown an 20 apertured rubber lift and an apertured metallic attaching plate therefor, the two being permanently secured together by means of substantially L-shaped tongues which project laterally from the plate and are embedded in the rubber lift, the plate also including spurs to enter the usual leather heel to prevent rotation and shifting of the rubber heel, there also being a retaining screw to pass through said apertures into the 30 leather heel to secure the rubber heel in place.

Upon manufacturing several heels constructed in accordance with the structure disclosed in my patent, I find that the type 35 of anchoring tongues do not properly retain the plate and lift together, therefore, I find it necessary to change this particular part of the heel in order to obtain a heel of this type in which there is little or no possibility of 40 the heel and plate separating.

To overcome the above objection, I have devised and here disclose, an attaching plate provided with novel anchoring tongues which not only differentiate the present device 45 from my patent, but also differentiate it from similar patented devices, a number of which I am entirely familiar with.

In the accompanying drawings forming a 50 part of this specification and in which like numerals are employed to designate like parts throughout the same:

Figure 1 is a top plan view of a heel and an attaching plate constructed in accordance with the present invention.

55 Fig. 2 is a transverse vertical section

taken on the line 2—2 of Fig. 1, showing the heel attached to a leather heel.

Fig. 3 is a detail top plan view of the new attaching plate.

In the drawings, wherein for the purpose 60 of illustration is shown a preferred embodiment of my invention, the numeral 1 designates a leather heel of a shoe 2, and the numeral 3 designates, as a whole, my improved rubber heel and attaching plate. In 65 view of the fact that the construction of the present device is only slightly different from that disclosed and claimed in the aforesaid patent, I do not deem it necessary to prepare a lengthy detail description of the old parts 70 of the device. Briefly described my heel includes a rubber, centrally apertured lift 4, recessed in its upper surface to provide a seat for the reception of the attaching plate 5. The latter, like the one disclosed in my 75 patent, is centrally apertured and is provided with a depressed portion 6 to compel the periphery of the rubber heel to bind against the heel-proper, when my device is attached. In addition to this, the plate is 80 provided with a plurality of upstruck V-shaped spurs 7 which are spaced inwardly from the margin of the plate and are adapted to engage the heel 1 to prevent rotation or displacement of the rubber heel as 85 is obvious.

So far as described, these parts are identical with my patented device. As before stated in my patent, the design of the anchoring tongues is such that the attaching 90 plate and lift will not remain permanently connected, as is desired. The construction overcoming this disadvantage is clearly shown in Fig. 3. Examination of this figure will disclose the fact that the plate is provided entirely around its margin with a plurality of dove-tail notches 8, the material between these notches forming dove-tail anchoring tongues 9, which when in use are bent downwardly at right angles close to 100 the body of the plate as shown in Fig. 2. When so bent, the points 10 of the adjacent tongues will almost contact each other, thus a perfect anchor will be had, and there will be little or no possibility of the attaching 105 plate and lift separating, which is a disadvantage attached to my patented device and similar devices with which I am familiar. My heel may be secured to the heel-proper by means of a fastening screw 11 which may 110

be passed through the apertures in the lift and plate, and into the leather heel. While the constructional differences between the patented device and the present device are 5 only slight, I find that there is enough difference to turn a failure into a success. In view of the foregoing remark, I desire to emphasize the construction of the anchoring tongues of the present attaching plate be- 10 cause it accomplishes the result desired, in a very effective manner. In addition to this, it is strong, durable, and extremely inexpensive to both the manufacturer and the user.

A careful consideration of the foregoing 15 description taken in connection with the accompanying drawings will enable persons skilled in the art to which this invention relates to, not only distinguish the difference between my patented device and the present 20 device, but will also enable them to obtain a

thorough understanding of the objects and advantages claimed for the latter. In view of this, a more lengthy description is deemed unnecessary.

I claim:

A shoe heel comprising an apertured rubber lift and an apertured attaching plate, therefor, the apertures being in alinement with each other, said plate resting on the attaching face of the lift and having its entire 30 margin provided with a plurality of spaced dove-tail notches, forming between them a plurality of spaced dove-tail tongues bent down at right angles to the body portion and embedded in the lift to permanently 35 connect the latter and plate together.

In testimony whereof I have hereunto set my hand.

LOUIS CUVELIER.
